COLLAPSIBLE TUBE AND SUPPORTING
BRACKET THEREFOR

Ruby R. Vale, Milford, Del.

Application May 6, 1942, Serial No. 441,892

1 Claim. (Cl. 222—100)

To the best of my knowledge and belief, all prior attempts to make collapsible tubes for pasty material, such as tooth-paste, soap, shaving cream and the like, out of other substances than soft metal or alloy thereof have failed. This is apparently due to the fact that no material was found sufficiently strong to retain the pasty material, sufficiently impervious to moisture and mild acids or alkalis in the packaged material, and yet sufficiently pliable to be readily collapsed by hand or manually operable devices to expel the material contained therein.

It is the purpose of my invention to avoid these difficulties by providing a collapsible tube of a non-metallic material such as a plastic or thermoplastic; for example, that sold under the trade-marks respectively "Lucite" or "Cellophane," "Plexiglas" or the like.

In order to protect a collapsible tube made of such plastic material, I provide a casing or envelope therefor which may be readily portable to contain, envelop and support the collapsible tube therein and which may also be readily attached to a wall or other convenient place and form a convenient holder, envelope or casing for the collapsible tube in a convenient position for dispensing its contents.

In general, therefore, my device will be seen to consist of a closed tubular cylinder or other shape of relatively rigid plastic material, a collapsible tube of relatively pliable plastic material having a neck portion, and a connecting ring or annular member having interengaging screw-threads between the ring member and the casing and between the ring member and the neck of the collapsible tube; so that, when said two sets of screw-threads are engaged and the ring member rotated, the casing and the ring member and the tube and the ring member are drawn into and firmly held or clamped in a rigid, tight support, whereby the casing forms a reinforcement or protection for the collapsible tube.

It is a further feature of my invention that the collapsible tube abuts against and hence is supported by the outer casing or supporting member. Thus it will be seen that the collapsible tube and its pasty, liquid or semiliquid contents are supported or held in both a vertical and horizontal direction. Moreover, due to the engagement therebetween, the end of the collapsible tube opposite from its neck or outlet may be rolled around a spool carried by a key or the like, and, the torque and torsion of this operation being assisted by the outer casing, the con-

tents of the collapsible tube by pressure are expelled from the outlet of the neck.

For a further exposition of my invention, reference may be had to the annexed drawing and specification and at the end thereof my invention will be specifically pointed out and claimed.

In the drawing:

Fig. 1 is a side elevation of my device with parts broken away in longitudinal cross-section.

Fig. 2 is a front elevation of my device with parts broken away in longitudinal cross-section.

In that embodiment of the invention chosen from among others for illustration in the drawing and description in the specification, my device is shown as consisting of an elongated tube or cylinder or of any form preferably made of relatively rigid plastic material such as that sold under the trade-name "Lucite." At its upper or top end, the casing or envelope 1 has screw-threads 2 thereon which intermesh with screw-threads 3 in top 4. Casing 1 may carry an ear 5 having a perforation 6 therethrough for the purpose of supporting the casing and the tube carried thereby in any convenient or desirable location. The casing 1 has, in one side, a longitudinal slot 7 for a purpose hereinafter more fully described.

Within casing 1, there is provided a collapsible tube 8 made of a relatively pliable or deformable plastic material preferably, but not necessarily, such as that sold as "Plexiglas" or under the trade-name "Cellophane." This tube is formed of a cylindrical body portion having its upper or closed end 9 joined together by heat or pressure so that the material of the collapsible tube unites itself together or is united by means of a separate adhesive or cement or is held closed by means of a separate clip (not shown in the modification illustrated). At its opposite or lower end, collapsible tube 8 has an end or breast portion 10 either formed by a thickened wall of the material itself or, as is shown in the example illustrated, by means of a perforated disk-shaped member into which bent-over flanges 11, at the ends of the walls of the tubular part, are molded or formed during the manufacturing operation. The breast portion 10 has an outlet 12 extending therethrough and carries, at its opposite face, a neck or nipple 13 having screw-threads 14 on its outer surface. Neck 13 carries thereon a cap 15.

Casing 1 and tube 8 are connected together by an annular member such as a connecting ring 16 which has an upstanding flange 17 at its outer rim or edge. The inner surface of flange 17 is

formed with screw-threads 18 which interfit with like screw-threads on the lower end of the tubular body of casing 1. Connecting ring 16 has a central opening therethrough of approximately the same size as neck 13 and having screw-threads 19 thereon which mate or interfit with the screw-threads 14 on neck 13.

Through slot 7 projects a key 20 having a head 21 adapted to be grasped by the hand of the user and having, at its inner end, an eye indicated at 22 through which the closed end 9 of the collapsible tube 8 may be passed as is best seen in Fig. 2. The outer surface of key 20 surrounding the slot 22 therein is formed in the shape of two frusto-conical surfaces 23. This is to insure that the material of the collapsible tube 8, as it is wound upon key 20, is guided towards the center and, as far as possible, away from the walls of the outer casing or support 1.

It is trusted that the method of assembly of my device will be readily understandable from the foregoing description. The top 4 may be removed and the collapsible tube 8 inserted through it or the collapsible tube may be inserted into the open lower end of the body of the casing 1 when the connecting ring 16 is removed. In either case, the cap 15 is removed from the neck 13 and the screw-threads 14 started into the screw-threads 19 on the connecting ring 16. To insert the collapsible tube from the upper end of the holder 1, the cap 15 is removed and the threads 14 on the neck of the collapsible tube are engaged with the threads on the ring or element 16. Thus, the collapsible tube is held down in the holder 1. The cap 15 is then screwed onto the neck or nipple of the tube. To insert the collapsible tube from the lower end of the holder 1, the element 16 is removed and

the cap 15 is detached from the empty tube. The threaded neck on the tube is screwed into the element or ring 16. The cap 15 is applied to the neck of the tube. The tube is inserted into the holder 1 and the element or ring 16 is screwed onto the holder.

If desired, the ear 5 may be omitted and the casing 1 used as a package or container during the sale and transportation of the inner collapsible tube 8 and the material therein.

If desired, the screw-threads 2 and the screw-threads 18 may be made of the same pitch so that the cap 4 and the ring-shaped member 16 may be made duplicates, the hole in the ring-shaped member being closed by a layer of paper or other readily removable closure which would be omitted when the element is used as the ring-shaped member 16.

It will be obvious to those skilled in the art that modifications may be made in details of construction and in matters of mere form without departing from the spirit of the invention.

I claim:

A container comprising a collapsible tube, a casing for the same provided with a longitudinal slot and a key extending through the slot and having an opening therein adapted to receive one end of the tube, the outer surface of the key surrounding the opening being in the form of two conic frustums having their larger bases spaced and having their smaller bases coinciding and arranged in abutting relation so as to give the rolled up material of said tube clearance from the walls of the surrounding casing and so as to draw it toward the middle of the key.

RUBY R. VALE.
